UNITED STATES PATENT OFFICE.

THOMAS R. WILLIAMS, OF YOUNGSTOWN, OHIO.

MOLD FOR BUILDING-BLOCKS.

1,277,674.

Specification of Letters Patent. Patented Sept. 3, 1918.

Application filed June 26, 1918. Serial No. 242,064.

To all whom it may concern:

Be it known that I, THOMAS R. WILLIAMS, a citizen of the United States, residing at Youngstown, in the county of Mahoning 5 and State of Ohio, have invented certain new and useful Improvement in Molds for Building-Blocks, of which the following is a specification.

This invention relates to the general sub-
ject of a molding apparatus, and has partic-
ular reference to a device for forming
building blocks of different shape.

To this end, the invention contemplates a mold including novel wall portions which 15 may be readily assembled in any one of several different positions to provide a differently shaped interior mold box, whereby a variety of matching blocks may be formed from the same mold. That is to say, it is 20 proposed to so construct the mold that the blocks made therein will be of the same general dimensions with complementary matching end portions which will readily interlock to provide a flat wall surface, finishing 25 edge, or a wall corner.

A further and more specific object of the invention is to provide a mold structure which is simple, cheap and efficient, and readily assembled and manipulated to form 30 the differently shaped blocks.

With the above and other objects in view which will more readily appear as the nature 35 of the invention is better understood, the same consists in the novel construction and arrangement of parts hereinafter more fully described, illustrated and claimed.

A preferred and practical embodiment of the invention is shown in the accompanying drawings, in which:—

40 Figure 1 is a plan view of my improved molding apparatus.

Fig. 2 is an end view thereof.

Fig. 3 is a side elevation thereof.

45 Fig. 4 is a top plan view, similar to Fig. 1, but showing one of the end walls of the mold reversed to provide a substantially T-shaped block.

50 Fig. 5 is another top plan view showing a further arrangement of the end wall of the mold to provide a substantially L-shaped block.

55 Figs. 6, 7 and 8 are respectively top plan views of the blocks formed by the mold structure shown in Figs. 1, 4 and 5 of the drawings.

Fig. 9 is a top plan view of an integral mold box structure for forming the type of block shown in Fig. 6, which block is also formed by the structure shown in Fig. 1.

Fig. 10 is a side elevation partly in sec- 60 tion, of the structure shown in Fig. 9.

Fig. 11 is an end elevation thereof.

Fig. 12 is a transverse sectional view on the line 12—12 of Fig. 9.

Similar reference characters designate cor- 65 responding parts throughout the several figures of the drawings.

As previously indicated, a primary object of the present invention is to provide a single mold device which is capable of forming 70 differently shaped interlocking blocks which may be readily utilized to meet all of the requirements of building a wall or like structure. Also, to provide a construction which may be adjusted and arranged to make a set 75 of interlocking blocks adapted to be used to form the flat face of a wall, a corner there-
of, or a finishing edge for a window open-
ing, such for instance as shown in Figs. 6,
7 and 8 of the drawings, wherein Fig. 6 80
shows a block or tile generally utilized in
forming the face of the wall, while Fig. 7
shows a block which may be conveniently
employed in making a right angle corner of
a wall, and Fig. 8 shows a block which may 85
be used in providing a finishing edge for a
window opening.

Referring more particularly to the molding apparatus intended to form the blocks having the characteristics above set forth, it 90 will be observed from Fig. 1 of the draw-
ings that the mold essentially consists of the
relatively long flat side wall members 1 and
2, and the special end wall sections 4 and 5
which are adapted to be shifted or reversed 95
to form the different end portions of the
blocks. As will be observed from the draw-
ings, the end section 4 consists of a wall 6,
having a flat face 7 at one side thereof while
the opposite side is provided with a prefer- 100
ably rectangular offset core member 8 whose
height is commensurate with that of the side
wall 1, and is adapted to occupy a corner of
the interior space of the mold when the side
walls 1 and 2 and end sections 4 and 5 are 105
in assembled relation.

For the purpose of maintaining the side 110
walls 1 and 2 in position with respect to the
end sections 4 and 5 the latter may be pro-
vided with the upstanding ears 9 for receiv-

ing a relatively long clamping rod R which has engaged with the opposite ends thereof suitable vertical clamping bars 10 for holding the side walls 1 and 2 against the edges 5 of the wall portions of the said sections when the nuts or equivalent fastenings 11 are screwed on the threaded ends thereof. To further assist in clamping the side walls to the end sections the clamping bars 10 10 may carry at their lower ends the binding screws 12.

The end section 5 is similar in its general structure to the section 4, but unlike the latter section is provided with a double offset 15 core member to increase the range of utility of the mold. That is to say, this end section 5 includes a wall portion 13 carrying at one side of its center the oppositely projecting similar offset core members 14 and 20 15 whereby it may be readily reversed to shift the core members from one corner of the box to another.

In the assembly shown in Figs. 1, 2 and 3 of the drawings it will be observed that the 25 interior shape of the mold is of substantially Z-shaped formation, and if desired a center core C of suitable shape may be placed within the same to make a hollow block, and, with the mold assembled as shown it will 30 be seen that any desired number of blocks may be formed of this shape, the mold, of course, resting upon a suitable support or base which constitutes the bottom of the mold. After the molding material has set 35 the side walls may be slightly eased by loosening the clamping bars 10 to effect the removal of the block.

When it is desired to form a block of the 40 shape shown in Fig. 7 of the drawings, that is, a substantially T-shaped block, it is only necessary to let the end section 4 remain in the same position as it is in Fig. 1, while the end section 5 is reversed from the position that it occupied in the latter figure to 45 that shown in Fig. 4. Thus, the reversing of the end section 5 has the effect of placing the core member 14 on the outside of the mold while the oppositely projecting core member 15 is disposed within the interior of the 50 mold and occupies a corner thereof opposite to that occupied by the core member 14 when the end section 5 is in the position shown in Fig. 1. Accordingly, it will be observed from the arrangement shown in Fig. 4 that 55 the interior of the mold is provided with corner core members both located on the same side of the longitudinal center of the mold, to thus provide a substantially T-shaped interior. Also, as shown, a suitable 60 central core member C' may be employed.

In forming the type of block shown in Fig. 8 of the drawings, the mold assembly of Fig. 5 is utilized. As will be observed from this figure the end section 5 may be left in 65 the same position as it was in Fig. 4, while

the end section 4 is reversed from the position shown in Figs. 1 and 4, whereby the core member 8 will be disposed outside of the box and the flat face 7 of the said end section 4 will constitute a smooth surface for forming a flat end face on the block. It will further be apparent that with the end section 4 arranged as shown in Fig. 5, the section 5 may be reversed, whereby it will occupy the same relative position it did in Fig. 1, thus 75 forming the shoulder on this type of block on the opposite corner, which may be desirable to suit certain requirements. In forming this type of block, as in the other types, a suitable center core portion C² may also 80 be employed.

As further illustrating the idea of providing a mold box wherein the opposite end wall portions are provided with inwardly projecting abutments for forming opposing shoulders on the finished block, reference may be made to Figs. 9, 10, 11 and 12 of the drawings wherein a cast metal box is shown. In this form of the invention the mold box is designated generally as M, and consists 90 generally of the opposite side wall portions 16-16 and the end walls 17-17 each of which include the inwardly projecting core members 18 that coöperate with a central core portion 19 formed integral with the base 20 of the box and adapted to produce the desired central opening in the finished block. Furthermore, as will be observed from Figs. 11 and 12, the base 20 is provided with a suitable integral projecting shoulder 21 which together with a removable edge strip 22 detachably clamped as at 23 to the upper edges of the mold, provides a groove or recess at the upper and lower edges of the finished block. This form of the invention, 100 therefore provides for forming a substantially Z-shaped block similar in general configuration to the type of block adapted to be turned out by the mold shown in Fig. 1.

From the foregoing it will be apparent 105 that the present invention aims to provide a mold structure which is capable of producing a block having end portions adapted to interlock with other blocks turned out from the same mold, regardless of whether all of 110 the blocks are of the same general shape or configuration, but in each case preserving the same type of interlocking end.

I claim:

1. A molding apparatus comprising a box 120 having side and end walls, a core member arranged within the box and occupying the entire corner space between a side wall and an end wall and also spaced from the opposite side wall to provide a relatively restricted mold space, and a central core having its body portion arranged in spaced relation to the side walls and corner core member and provided with a relatively flat core projection located in said relatively restricted 125 130 135 140 145 150 155 160 165 170 175 180

mold space formed between a corner core and side wall.

2. A molding apparatus comprising a box having end walls carrying shiftable core members adapted to project into the interior of the box at the inner corners thereof, and a central core arranged in spaced relation to the corner core members.

3. A molding apparatus comprising a box 10 consisting of opposite side walls and reversible end sections carrying projecting core members, and means carried by the end sections for clamping the side walls in position with reference thereto.

15 4. A molding apparatus comprising a box consisting of opposite side walls and reversible core carrying end sections, and means for holding the side walls and end sections in assembled relation.

20 5. A molding apparatus comprising a box consisting of side walls, reversible end sections having offset core members adapted to occupy a corner of the interior of the box, and clamping bars carried by the end sec-

tions for holding the side walls in position 25 with reference thereto.

6. A molding apparatus comprising a box 30 consisting of side walls and opposite reversible end sections, one of said sections carrying a single offset core member and the other of said sections carrying a double core projection, and means for holding the side walls and end sections in an assembled relation.

7. A molding apparatus comprising a box 35 consisting of side walls and reversible end sections, one of said sections having a flat face and carrying on the opposite face an offset core member, and the other of said sections carrying oppositely projecting core members, and means for holding the side 40 walls and end sections in assembled relation.

In testimony whereof I hereunto affix my signature in the presence of two witnesses.

THOMAS R. WILLIAMS.
